CLAIM

The ornamental design for a high chair with a frame having reversed V-shaped legs and a shell-shaped chair with footrest, as shown and described.

DESCRIPTION

FIG. 1 is a perspective view of the high chair having the chair in its raised position;

FIG. 2, 3 and 4 are, respectively, lateral, front and rear views of the high chair shown in FIG. 1;

FIG. 5 is a perspective view of the high chair having the chair in its lowered position; and,

FIG. 6 is a lateral view of the high chair in its folded position.

The broken lines shown in FIG. 4 around the edge of the seat cover represent stitching.
